UNITED STATES PATENT OFFICE.

ANTHONY E. WALLER, OF EDGEWOOD, RHODE ISLAND.

JOINT FOR PIN TONGUES.

1,403,276.

Specification of Letters Patent. Patented Jan. 10, 1922.

Application filed September 8, 1919. Serial No. 321,384.

To all whom it may concern:

Be it known that I, ANTHONY E. WALLER, a citizen of the United States, and resident of Edgewood, in the county of Providence and State of Rhode Island, have invented 5 certain new and useful Improvements in Joints for Pin Tongues, of which the following is a specification.

This invention relates to joints for pins, 10 and has for its object to provide a joint member constructed with fulcrum fingers formed integral on the forward periphery of each ear, said fingers being bent toward each other to provide a forward fulcrum for the 15 pin-stem.

A further object of the invention is to provide the bridge portion of the joint member that is very short in length relative to the diameter of the side ears, said bridge 20 being provided with bendable legs for connecting it to a suitable base.

With these and other objects in view, the invention consists of certain novel features of construction, as will be more fully described, and particularly pointed out in the 25 appended claims.

In the accompanying drawings:

Figure 1— is an elevation of the joint member partly in section, the same being 30 shown as connected to a base plate.

Figure 2— is an enlarged view showing the shape of the joint member as blanked out of sheet stock and the relative shape and position of the fulcrum fingers.

Figure 3— is an enlarged front elevation of the joint member, showing the fulcrum fingers bent forward toward each other with their ends abutting.

Figure 4— is an enlarged sectional elevation of the joint member, showing the base in dotted lines, to which the joint member is designed to be attached.

Figure 5— is a top view of the base member.

Referring to the drawings, 10 designates 45 a base member which is herein illustrated as made in an inverted bowl-shape and adapted to be connected to a celluloid bar 11 by being expanded in a recess 12 formed in the 50 bar.

My improved joint member is preferably constructed from sheet metal stamped out into the form best illustrated in Figure 2, with ears 13—13. On the forward edge or 55 periphery of each ear is formed a narrow finger portion 14, the upper edge of each

finger being substantially the same height from the bridge as through the center of the pivoting point in the ears.

The base portion 16 of each finger is 60 comparatively narrow and forms but a very small portion of the circumference of the ear, that is the base of the finger does not extend down to the bridge portion 17 of the joint member, thereby permitting this 65 bridge portion to be made comparatively short in length, or of a length which is somewhat less than the diameter of the ears.

On the opposite ends of this bridge portion, I have formed bendable legs 15 which 70 of necessity must be comparatively close together so that they may pass through the openings 18 in the base member 10, which base member it is found in practice should be made small and inconspicuous as possible 75 and it is therefore found to be necessary that the whole of each of these fingers should be supported on the periphery of the ear instead of extending down to said bridge portion as is the case with some other constructions.

After punching this blank from the sheet metal I bend the ears up from the common base or bridge portion 17 into the form illustrated in Figure 3, whereby the ears are 85 parallel and spaced apart and between which the pin-tongue 19 is adapted to be pivotally mounted. The fingers 14—14 are bent toward each other from the opposite ears so that their ends abut at 20. In this position it will 90 be seen that the pin stem 19 when mounted on the center pivot, or inwardly extending protuberances, as the case may be, its lower edge, as shown in Figure 1, rests upon these fulcrum fingers and serves to provide the 95 necessary spring or tension to hold the pointed end into engagement with the catch member 20.

By my improved construction of providing a fulcrum of fingers formed integral with 100 the forward edge of the joint ears I am enabled to use the most inexpensive form of pin-stem which is that of bending one end of the round wire of the pin into an eye as illustrated in Figure 1.

The legs 15—15 may be bent downward 105 and passed through corresponding eyes in the base plate and then bent back with the ends abutting against each other as illustrated in Figure 1, thereby forming a very 110 secure fastening to the base and that without the use of solder.

In practice the pin-stem and the joint connected to the base member 10, is sold as a complete finding to jewelers who do the mounting and finishing of the article ready 5 for the trade.

I claim:

A pin-stem joint member formed of thin sheet stock folded to form a short bridge portion with two spaced apart upstanding side 10 ears integral with the opposite edges of the bridge and adapted to mount a pin-stem in

the space between them, a pair of bendable fulcrum finger each having one end formed integral with the forward edge of each ear, said fingers extending inwardly toward each other to extend across this space with their free ends abutting to provide a fulcrum-bearing for the pin-stem, said bridge being provided with means whereby it may be readily connected to a base-member. 20

In testimony whereof I affix my signature.

ANTHONY E. WALLER
